DESIGN FOR A CIGAR HUMIDOR DISPLAY CASE

Robert B. Wemyss, Louisville, Ky.

Application October 14, 1944, Serial No. 115,773

Term of patent 7 years

(Cl. D80—11)

To all whom it may concern:

Be it known that Robert B. Wemyss, a citizen of the United States, residing in Louisville, county of Jefferson, State of Kentucky, has invented a new, original, and ornamental Design for a Cigar Humidor Display Case, of which the following is a specification, reference being had to the accompanying drawing forming part thereof.

The figure is a perspective view of a cigar humidor display case showing my new design, the end not disclosed is the same as that shown and the rear is plain.

I claim:

The ornamental design for a cigar humidor display case, substantially as shown and described.

ROBERT B. WEMYSS.
